UNITED STATES PATENT OFFICE.

FREDERICK W. HORSTKOTTE, OF SPOKANE, WASHINGTON.

LUMBER PILER.

Application filed November 18, 1924. Serial No. 750,690.

To all whom it may concern:

Be it known that I, FREDERICK W. HORSTKOTTE, a citizen of the United States, residing at Spokane, in Spokane County and State of Washington, have invented certain new and useful Improvements in Lumber Pilers, of which the following is a specification.

My present invention relates to improvements in lumber pilers adapted for use in a variety of ways but particularly designed for stacking lumber on trucks or cars, which when loaded, are conveyed to a drying kiln.

The invention contemplates the utilization of an upright conveyer of the endless chain type for successively elevating and depositing boards or planks on a chute or skidway in combination with a vertically movable stacking or piling frame upon which the workman stands while handling the lumber and forming the stack on the kiln truck. Means are provided for adjusting the stacking frame for various lengths of boards or planks; automatic devices are used for guidance in piling the boards or planks in the stack for the formation of a flue in the stack or pile to insure proper distribution of the air currents in drying the material after the loaded truck has been introduced to the kiln; and other meritorious features and combinations and arrangements of parts are utilized to insure facility and accuracy in the formation of the stack, as will herein after be more fully pointed out and claimed. In the accompanying drawings I have illustrated one complete example of the physical embodiment of my invention wherein the parts are combined and arranged in accordance with the best mode I have thus far devised for the practical application of the principles of my invention.

Figure 1 is an end view of the lumber piler embodying my invention showing diagrammatically and in dotted lines a completed stack with the central flue therein.

Figure 2 is a view in front elevation of the lumber piler partly broken away at intermediate points and showing also the two end platforms also broken away for convenience of illustration.

Figure 3 is a top plan view of the lumber piler with some parts omitted.

Figure 4 is an enlarged detail view in ele-

vation of the releasing device for the movable, intermediate carriage to permit adjustment of the latter.

Figure 5 is an enlarged, detail perspective view of one of the guides for the sticks used as separators placed in horizontal position between layers of boards in the stack.

Figure 6 is a sectional detail view at line 6-6 of Figure 4.

In carrying out my invention I utilize a strong supporting frame comprising spaced uprights or posts in the form of channel bars 1 and 2, provided with suitable bases and joined by a cross beam as 3 to insure a rigid structure for operating parts of the apparatus.

The upright conveyer is made up of a plurality of similar units supported from this main frame, and each unit is provided with a lower shaft 4. The upper shaft 5 common to all of the units is journaled in the upper ends of upright frames 6 having suitable bearings 7. These frames form guide ways for the three endless chains 8 which pass around sprocket wheels 9 and 10 at the lower and upper ends of these frames. The chains are actuated by power applied to a sprocket wheel 11 on the shaft 5 actuated from a suitable source of supply.

Each chain of the elevator units is equipped with a series of lumber carriers 85 each comprising a pair of duplex arms 12 and 13 pivoted at 14 on the chain, and the free ends 15 of these arms serve to maintain the carriers in proper position regardless of the location of the carriers on the endless chain.

As seen in Figure 1 a plank or board 16 is deposited on a plurality of the spaced brackets 17 supported from the main frame, and by manual feed these planks are picked up and placed upon the synchronously moving lower arms 12 of the aligned carriers.

As the carriers move upwardly as indicated by the arrows in Fig. 1 the boards or planks are carried by them up and over the top of the carrier frames, and the planks are then deposited upon a series of spaced inclined skids 18 in the form of angle irons which project at the front of the machine.

As the boards are discharged upon the skids 18 they are handled by two men and deposited upon a car or kiln truck 19, in the form of a stack having a central flue 20 as

indicated by dotted lines and full lines in Figure 1. The flue 20 as shown has a wide base and its walls converge or taper toward the stack-top. The planks or boards are 5 laid or built up in the stack in such manner that laterally extending spaces are provided therein to facilitate the distribution of air currents through the stack when the lumber has been conveyed into the kiln for drying.

10 In stacking the lumber on the kiln truck it is also necessary for greatest economy and efficiency to space the horizontally disposed sticks 21, which are used to separate the 15 layers of planks or boards, at proper intervals and in regular order, in the stack in uniform vertical rows.

The lumber is removed from the skids 18 by two men, one at each end of the plank or board, who stand upon the end platforms 20 22 and 23 provided therefor. A third, intermediate, platform 24 is also utilized by one man when short lengths of material are being handled, and this third platform is 25 adjustable between the two end platforms in order that a man may stand thereupon and co-operate with another man on one of the selected end platforms. When long boards are being stacked, the auxiliary platform 24 is moved to the right in Figure 3 30 adjacent to the platform 24 and used in conjunction with that platform.

The platforms are designed for vertical movement starting from their lowermost position when the first layer of material 35 is deposited upon the kiln truck 19, and they are gradually elevated or lifted, as the stack rises under formation, to their uppermost positions as indicated in Figures 1 and 2.

40 The three platforms are each suspended by frames 25, or 25' for the intermediate platform, from a vertically movable, horizontally disposed, rectangular stacking frame made up of a pair of end beams 26 26' and two side beams 27 27'. The end beams which project beyond the side beam 27 are fixed in suitable manner each to a vertical slide head 28 28' which heads are 45 guided in their vertical movement by the respective posts or uprights 1 and 2.

50 The stacking frame is suspended by cables 29 29' which are attached at 30 to the respective heads and these hoisting cables pass upwardly over pulleys 31 on the elevating shaft 32 which is journaled in bearings 33 55 at the upper ends of the posts 1 and 2. One of the cables, as 29 (see Fig. 2) also passes around an idle pulley 34 and thence over a driven pulley 35 on the elevating shaft 60 and back to a driving pulley 36 supported in a yoke 37 on the end of a piston rod 38 having a piston (not shown) in the hydraulic cylinder 39. Pipes 40 and 41 provide the proper connections for the motive fluid to the cylinder for hoisting and lowering the 65 stacking platforms and frame. A control

valve 40' for the motive fluid (Figs. 1 and 2) in connection with the pipes 40 and 41, is operable from the platform 22, in any position, by the man standing thereon, who manipulates a valve rod 41'. This rod has 70 a hand lever 42 at its upper end and at its lower end has a socket head 43 for engagement with the valve 40' and the rod is of sufficient length to be accessible for the operator when the stacking frame with its 75 platforms is elevated.

The control of the hydraulic jack is such that the platforms and stacking frame are gradually elevated as the stack is built upwardly, but the stacking frame with its 80 platforms may quickly be lowered to its lowermost position after a truck has been loaded and moved away from the piling machine.

The boards or planks which are laid longitudinally of the machine and on the truck 19, are separated in layers by successive tiers of spacing sticks 21 and the central longitudinal flue 20 is formed in the stack with a wide, open base, and a closed narrow 90 top, by means of automatically operated guides carried on the stacking frame, as will now be described.

These guides are arranged in pairs, one 95 pair being carried by each of the end beams 26 26', and another pair carried by a beam 45 forming part of the intermediate platform. Each guide comprises a pair of opposed, flanged metallic plates 46 and 47 having perforations and reversed screw threads for the complementary right and left hand threaded screw bars 48, 49, and 50. The guide plates are retained and guided each in a slot 51 of the guide-supports, and the screw bars are journaled to 100 revolve in bearings 52. The end screw bars 48 and 49 extend over to the respective heads 28 and 28' and each bar, is provided with a rack wheel as 53 which is rotated or 105 revolved with its screw bar as the wheel travels upwardly or downwardly in contact with a vertical rack bar 54, one secured at the outer side of each of the uprights 1 and 2 of the main frame. When the stacker frame is in lowered position these guide plates 46 and 110 47 are spaced apart their maximum distance for indicating the position of the inner boards of the two sections of the first layer of the stack deposited upon the kiln truck 19.

115 As the stacking platform gradually rises under propulsion from the hydraulic jack, and through the action of the rack bars, rack wheels and screw bars, the guide plates are gradually brought together in order that when the stacking frame rises to its maximum height as in Figure 1, the guide plates 120 are at their minimum distance apart. By using these plates as guides the men are 125 enabled to stack the timber with facility as 120

indicated in Figure 1 to form the flue 20 for use in the kiln. After the stack is completed and the loaded truck disposed of, the guide plates are automatically separated to their maximum distance as the stacking frame descends to its lowermost position.

In addition to these guides employed in piling the boards to form the stacks, I also utilize guides in laying the alternating tiers 10 of sticks 21 on top of the layers of boards. These stick-guides comprise channel plates 55 spaced at regular intervals in two complementary series on the inner sides of the two beams 27 and 27'. The guide plates 55 are disposed in vertical position and are interchangeable and adjustable. Each guide plate is provided with a pair of spaced headed bolts 56 and these headed bolts are adapted to engage the complementary pair of key-hole slots 57 on the frame bars 27 27' in order that the guide plates may with facility be attached or detached with relation to their supports, and adjusted at various distances apart along the inner sides of the beams. 20 The sticks 21 which are uniform in length are dropped into position on the truck or on the stack, with their ends passing through a pair of complementary guide plates to insure their proper position and uniform spacing 25 at proper intervals along the stack. As each layer of planks is laid longitudinally of the truck, a tier of sticks is quickly laid transversely of the planks, until the stack is completed as indicated in Figure 1. Then 30 the top open end of the flue 20 is closed by a single plank to form a barrier against a direct updraft through the flue. By this arrangement of the flue in the stack and the spaces between layers of planks the heated air currents in the kiln are caused to move laterally from the inner flue towards the outer sides of the stack, to insure uniform, distribution of the air currents, and consequent efficiency, in drying the material.

The intermediate platform 24, together with its frame 25' and a beam 47 of the platform, form a carriage which is movable longitudinally of the stacking frame. The carriage is provided with pairs of rollers 58 at 45 its ends which run upon the top surfaces of the respective beams 27 27' as rails or guides therefor. This roller supported carriage with its platform may thus be moved manually to the desired position intermediate the two end platforms 22 and 23, and used by one of two men with a selected end platform in stacking short lengths of material received from the skids 18.

The stacking guides 46 and 47 of the carriage or intermediate platform are actuated in unison with the actuating means for the stacking guides of the end platforms, through the instrumentality of a sprocket chain 59, the upper and lower flights of 60 which engage a sprocket wheel 60 on the end

of the screw bar 50 of the carriage or intermediate platform. When short length planks as 61 are being handled, this chain is actuated to operate the stacker guides 46 and 47 of the carriage, the latter being retained in adjusted position for use by one of the men handling the planks.

The screw bar 50 of the carriage passes through a slot 62 in the side beam 27, and the chain 59 is supported on sprocket wheels 75 63 and 64, the latter wheel being carried on one of the end screw bars, as 49 of the machine, and revolved therefrom.

The sprocket wheel 63 at the other end of the endless chain 59 is journaled in a yoke 80 65 which has a suitable suspending bar 66 slidably supported in a bracket 67 on the beam 27. A spring 68 is coiled about the slide bar and interposed between the bracket 67 and an adjusting nut 69 on the threaded end of the adjusting bar. The sprocket wheel is thus suspended in a tension device to maintain the sprocket chain in co-action with its sprocket wheel 60 on the carriage, and this tension device also permits release 90 of the chain from the sprocket wheel 60 in order that the carriage may be free to move to adjusted position when short lengths of material are to be handled.

The chain 50 is normally held in operative relation to its wheel 60. When the carriage is to be moved to adjusted position intermediate the end platforms, the chain flights are disengaged from the sprocket wheel 60 by turning a hand lever 70 (see 100 Figure 4) which is pivoted on the screw bar 50. This hand lever is provided with a pair of spaced rollers 71 and 72 located at proper points on the lever to contact with the inner faces of the two chain flights as the lever is turned from normal horizontal position to vertical position as shown by dotted lines. As the lever is turned upwardly or downwardly, the two rollers engage the chain flights and spread them apart, thus 105 freeing the chain from the wheel. This permits movement of the carriage which movement also includes the sprocket wheel 60 and the screw bar 50, the latter sliding along in the slot 62 of the beam 27.

For retaining the lever 70 in normal position a pin 73 is passed through a perforation in the lever and said pin projects into the slot 62 of the beam 27 to hold the lever against accidental displacement while the 120 chain 59 is operating.

From the above description taken in connection with my drawings it will be evident that I have provided a lumber piling machine which may be utilized for quickly and conveniently stacking or piling the material upon a truck, car, or other carrier as required and hereinbefore explained, and that the machine will perform its functions with smoothness and regularity and reliability.

Having thus fully described my invention, what I claim as new and desire to secure by Letters Patent is—

1. The combination with discharging skids, of a main frame, a vertically movable stacking frame supported on the main frame adjacent to said skids, normally spaced guides on said stacking frame, and means for moving said guides toward the center of the stack as the height of the latter increases.

2. The combination in a lumber stacker with a main frame, a vertically movable stacking frame supported thereon, and means for moving said stacking frame, of automatically operated guide means on the stacking frame whereby a flue may be created in a stack while the latter is building.

3. The combination in a lumber piler with a main frame, a vertically movable stacking frame supported thereon and actuating means for the stacking frame, guide devices on the stacking frame for use in creating a flue in a stack while said stack is being erected, and means co-acting with the main frame and stacking frame for moving said guide devices.

4. The combination in a lumber piler with a main frame, a vertically movable stacking frame supported thereon and actuating means for the stacking frame, normally spaced stacking guides on the stacking frame and means for moving said guides toward the center of a stack with the upward movement of the stacking frame, and stick-guides carried by said stacking frame for use in erecting a stack.

5. The combination with a supporting frame of a vertically movable stacking frame and means for operating said stacking frame, of a pair of spaced platforms carried by said stacking frame, an auxiliary platform carried by said stacking frame and means for moving said platform relatively to the spaced platforms whereby the auxiliary platform may be moved adjacent to one of said fixed platforms.

6. The combination with a supporting frame of a vertically movable stacking frame and means for operating said stacking frame, of a fixed platform on the stacking frame, a carriage on the stacking frame and an auxiliary platform on said carriage, stacking guides on the stacking frame and a stacking guide on the carriage, and means actuated by movement of the stacking frame for actuating said stacking guides.

7. The combination with a supporting frame of a vertically movable stacking frame and operating means therefor, of a plurality of stacking-guides carried by said stacking frame each comprising a pair of opposed, relatively movable plates and means actuated by the movement of the stacking

frame for varying the distance between 65 said plates.

8. The combination with a supporting frame of a vertically movable stacking frame and operating means therefor, of a plurality of stacking guides carried by said stacking frame each comprising a pair of opposed plates and a screw bar having reversed threads for each pair of plates, a rack wheel on each screw bar, and a rack bar on the supporting frame for each rack wheel. 75

9. The combination with a supporting frame of a vertically movable stacking frame and operating means therefor, of a pair of stacking-guide-members carried by said stacking frame a carriage on the stacking frame, a pair of stacking guide-members carried by said carriage, and means actuated by the movement of the stacking frame for varying the distance between said guide members. 85

10. The combination with a supporting frame, a vertically movable stacking frame, a working-platform on said stacking frame, and means for operating the stacking frame, of a carriage on said stacking frame and a working-platform on the carriage, a plurality of stacking guides on the stacking frame and a stacking guide on the carriage, each said guide comprising a pair of relatively movable plates, and a screw bar having reversed threads for co-action with said plates, a rack wheel on the screw bars carried by the stacking frame and a rack bar for each said wheel on the supporting frame, and operative connections between 100 one of said latter screw bars and the screw bar on the carriage. 95

11. The combination with a vertically movable stacking frame having a working platform and a screw bar supported on said frame, of a carriage supported on the stacking frame and a screw bar on said carriage, a pair of opposed stacking-guide plates on each screw bar and reverse threads on said bars, power transmission devices connecting said bars, and means actuated by the movement of the stacking frame for revolving said screw bars. 110

12. The combination with a main frame and a rack bar thereon of a vertically movable stacking frame and a screw bar thereon having a rack wheel, of a carriage on the stacking frame and a screw bar thereon, a pair of relatively movable guide plates on each screw bar, sprocket wheels on said bars 120 and a sprocket chain connecting said wheels. 115

13. The combination with a main frame and a rack bar thereon, of a vertically movable stacking frame and a screw bar thereon having a rack wheel, a carriage on the stacking frame and a screw bar thereon, a pair of relatively movable stacking guide plates on each screw bar, sprocket wheels on said 125

bars and a sprocket chain connecting said wheels, and means for releasing said chain from the carriage-sprocket-wheel to permit movement of the carriage.

5 14. The combination with a main frame and a rack bar thereon, of a vertically movable stacking frame and a screw bar thereon having a rack wheel, a carriage on the stacking frame and a screw bar thereon, a pair
10 of relatively movable stacking plates on

each screw bar, sprocket wheels on said screw bars, a third sprocket wheel having a movable support on the stacking frame, and means for releasing said chain from the carriage sprocket wheel to permit movement 15 of the carriage.

In testimony whereof I affix my signature.

F. W. HORSTKOTTE.
